BEAM BALANCE WEIGHING SCALE

Manfred K. Hegemann, Ferris Lane,
Upper Grand View, N.Y.

Filed Dec. 15, 1964, Ser. No. 83,042

Term of patent 14 years

(Cl. D52—10)

Fig. 1

Fig. 2

Fig. 3

Fig. 5

Fig. 4

FIG. 1 is a front elevational view of the beam balance weighing scale showing my new design;

FIG. 2 is a top plan view of the scale of FIG. 1;

FIG. 3 is an elevational view of one end of the scale, each end being substantially identical;

FIG. 4 is a rear elevational view of the beam balance weighing scale;

FIG. 5 is a fragmentary view of the bottom of the scale showing the legs as viewed in FIG. 3.

I claim:

The ornamental design for a beam balance weighing scale, as shown and described.
